UNITED STATES PATENT OFFICE

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

Application filed July 24, 1922. Serial No. 577,164.

To all whom it may concern:

Be it known that I, ALONZO E. RHOADES, a citizen of the United States, and a resident of Hopedale, county of Worcester, State of Massachusetts (whose post-office address is Hopedale, Massachusetts), have invented an Improvement in Warp Stop Motions for Looms, of which the following description, in connection with the accompanying drawing, is a specification, like characters on the drawing representing like parts.

This invention relates to warp stop motions for looms and more particularly to means for indicating the location of a dropped detector and the broken or abnormally loose warp, which has caused the loom to stop, so that the operator may readily locate and piece or place in proper condition the warp and start the loom.

The invention is an improvement upon an indicating means disclosed in the application of Patrick Keegan, Serial #575,523 filed July 17, 1922.

The object of the invention is to provide a simple and efficient form of mechanism which may readily be embodied in existing warp stop motions with a minimum amount of labor and expense. The object of the invention is further to provide a construction of indicating mechanism of a simple, positive and accurate nature and one not requiring any springs.

The nature and objects of the invention will appear more fully from the accompanying description and drawings and will be particularly pointed out in the claims.

In the drawings:

Fig. 1 is a front elevation of a portion of a detecting mechanism embodying a preferred form of the present invention;

Fig. 2 is a view in end elevation and partially in vertical cross section looking toward the left of Fig. 1.

Fig. 3 is a top view enlarged of a small section of one of the banks of the detectors and the warps corresponding thereto;

Fig. 4 is a view similar to Fig. 3 showing a dropped detector in twisted position with portions of the grasping bars by which the twisting action is secured.

A simple and preferred embodiment of the invention is illustrated in the accompanying drawings as applied to the well known

"Northrop" type of loom and in connection with a well known type of warp stop motion.

The invention is an improvement upon that disclosed in the application of Patrick Keegan aforesaid. It is, therefore, necessary to illustrate or describe in detail only those features of the construction of the loom directly concerned with the present improvement.

In this type of warp stop motion mechanism the detecting mechanism is mounted in a suitable position in the rear of the harness frames at the top of the loom. For this purpose a suitable frame work connected to and supported by the loom frame extends transversely of the loom in the required position. One of the supporting brackets by which this frame work is secured to the loom frame at the left hand side is illustrated. This frame work at each end comprises a suitable head 2 mounted upon the support 1 and secured thereto by a bolt 3. Between the heads and extending transversely of the loom directly beneath the warp sheet extend the longitudinal parallel flat bars 4 and 5. The warps 6 as they pass from the warp beam to the shed forming mechanism rest upon and are supported by the upper edges of these bars at opposite sides of the detectors. If, as herein illustrated, there is more than one bank of detectors, intermediate supporting rods such as 7 are provided extending between the heads 2 parallel with the bars 4 and 5 to support the warps between banks of detectors.

The detectors are in the form of thin, flat metal pieces 8. Each detector is provided with an aperture 9 through which its warp passes so that normally each detector is supported by the warp with the apertures 9 in the same plane as the top surfaces of the bars 4 and 5 and the rod 7. The detectors are guided so as to move vertically by means of long, vertical slots 10 formed therein and fitting over the flat, vertically disposed detector guide bars 11 which also extend transversely between the heads 2.

The detectors are shown as arranged in two banks but the number may be varied as desired.

When a warp breaks or becomes unduly

slackened the corresponding detector drops vertically and, in this type of mechanism, the lower end of the dropped detector comes between the serrated edges of a fixed bar or plate and of a rocking feeler bar.

This rocking feeler bar is constantly rocked by a moving part of the loom in a well known manner. Consequently its rocking motion is restrained by a dropped detector and this restraint of motion is utilized in a familiar manner to effect the stopping of the loom.

In the construction illustrated the fixed bar or plate 12 for the front bank of detectors is secured to the bottom of the bar 4 with its serrated edge 13 projecting rearwardly and the fixed bar or plate 14 for the rear bank of detectors is secured to the bottom of the bar 5 with its serrated edge 15 projecting forwardly. The rocking feeler bar 16 extends in longitudinal parallelism with the bars 12 and 14 and is serrated at both of its edges 17 and 18 so as to cooperate with both. This feeler bar 16 secures its 20 rocking movement from a shaft 19 upon which it is mounted by arms 20 secured to the shaft. This shaft 19 is mounted in suitable bearings in the bracket arms 21, one of which is shown in Fig. 1.

The construction thus far described is a familiar one to those skilled in the art. In this invention, however, the shaft 19 is not only journaled to rock in the bearings 21 but it also is capable of sliding longitudinally in the said bearings. During the normal operation of the stop motion mechanism only the rocking movement of the shaft 19 is utilized and the loom is stopped in the usual manner upon the dropping of a detector and the restraining thereby of this 35 rocking movement.

The present invention is concerned solely with the means for indicating the position of the dropped detector. The large number 45 or warps in the sheet and the inconspicuous character of the detectors render it very difficult for the operator to locate the dropped detector and the broken or slackened warp after the loom has been stopped. This invention utilizes the principle of the invention of the said Patrick Keegan wherein, after the loom is stopped, the dropped detector is twisted by a manual operation out of parallelism with the other detectors, thus 50 spreading apart the detectors and the warp and enabling the operator readily to observe the location of the dropped detector.

This twisting movement of the dropped detector is effected by sliding the feeler bar 55 16 longitudinally after it has grasped the dropped detector between its serrated edge and the serrated edge of the cooperating fixed bar 12 or 14. This sliding movement

twists the dropped detector into an angular position or out of parallelism with the other detectors and separates them to a marked extent as indicated in the enlarged view of Fig. 4.

In this invention the required sliding movement of the feeler bar or of the shaft 70 19, which in effect constitutes a portion of the feeler bar, is given by a simple form of lever construction so located that it may be readily grasped and operated by the operator of the loom. For this purpose the shaft 75 19 is provided with an arm 22 rigidly connected thereto, as by means of the set screw 23, and extending radially therefrom. This arm may conveniently be located near one end of the shaft 19. A lever 24 is mounted 80 in a generally vertical position and preferably at one end of the detector supporting frame. At its lower end this lever is connected at 25 to the arm 22. Its upper end is shaped as at 26 to form a suitable handle 85 and the length of the lever is such that this handle is in a position readily to be reached by the operator. This lever is fulcrumed in an eye or loop 27 extending from the supporting frame.

It will, therefore, be seen that, after the loom is stopped by a dropped detector, all that the operator has to do is to seize the handle 26 and move it transversely of the loom thereby, through the connections described, directly and positively sliding the feeler bar 16 longitudinally and twisting the dropped detector into a position such as shown in Fig. 4.

This mechanism is very readily applied to 100 existing warp stop motions because a very similar construction has heretofore been provided for rocking or jiggling manually the feeler bar. But in that case the part corresponding to the lever 24 has had no 105 function of a lever and has been so guided on the supporting frame as to move vertically. The mechanical changes, however, which are necessary to convert this old type of mechanism into one embodying the present invention are comparatively slight. It is only necessary to change the mounting of the part corresponding to 24 so as to turn 110 this part into a lever and then to remove from the mechanism any parts which prevent longitudinal movement of the shaft 19.

It will thus be seen that the indicating mechanism is of a very simple type, that it eliminates any spring action, that it is positive in its operation, and that it is readily controlled manually by the operator to give the desired twist to the dropped detector.

Having thus described my invention, what I claim as new and desire to secure by Letters Patent, is

1. In a warp stop motion for looms a

series of flat warp detectors normally supported in parallelism by the warps, a fixed bar extending longitudinally alongside of and beneath one set of edges of the detectors, a shaft mounted to rock and slide in bearings supported from the loom frame and extending parallel with the fixed bar, a cooperating bar carried by the shaft and extending longitudinally alongside of and beneath the opposite set of edges of the detectors, means operated by a moving part of the loom to rock the shaft and cause the cooperating bar with the fixed bar to grasp a dropped detector to effect the stopping of the loom, an arm connected to and extending radially from the shaft, a lever fulcrumed on the loom frame, connected to the arm and extending within reach of the operator, whereby, after the loom is stopped, the operator by swinging the lever may slide the shaft longitudinally and thereby twist the dropped detector out of parallelism with the other detectors and thus indicate the position of the dropped detector.

other detectors and thus indicate the position of the dropped detector.

2. In a warp stop motion mechanism for looms of the type described, journal bearings supported from the loom frame, a shaft mounted to rock and slide in said bearings, a feeler bar supported from said shaft in parallelism therewith, an arm connected to and extending radially from the shaft, a lever fulcrumed on the loom frame, connected to the arm and extending within reach of the operator, whereby, after the loom is stopped, the operator by swinging the lever may slide the shaft longitudinally and thereby twist the dropped detector out of parallelism with the other detectors and thus indicate the position of the dropped detector.

In testimony whereof, I have signed my name to this specification.

ALONZO E. RHOADES.
